(57) **CLAIM**

The ornamental design for encaustic metal tile, as shown and described.

DESCRIPTION

FIG. 1 is a perspective view of an encaustic metal tile showing my new design;

FIG. 2 is a front elevational view thereof; the rear elevational view is the same;

FIG. 3 is a top plan view thereof;

FIG. 4 is a bottom plan view thereof;

FIG. 5 is a side elevational view thereof, the opposite side being a mirror image of that shown; and,

FIG. 6 is an enlarged fragmentary view of FIG. 1.
